Primary Examiner — David Muller*Assistant Examiner* — Nathan Johnston(74) *Attorney, Agent, or Firm* — Maxey Law Offices, PLLC; Stephen Lewellyn(57) **CLAIM**

The ornamental design for a jewelry holder, as shown and described.

DESCRIPTION

FIG. 1 is a front elevation view of the jewelry holder in accordance with my invention;

FIG. 2 is a back elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is another front elevation view thereof.

The portions of the jewelry holder shown in broken lines form no part of the claimed design.

1 Claim, 5 Drawing Sheets(56)
